UNITED STATES PATENT OFFICE.

EDMUND A. SCHADE AND JOSEPH M. HANCE, OF NEW BRITAIN, CONNECTICUT, ASSIGNEES TO THE STANLEY RULE & LEVEL COMPANY, OF NEW BRITAIN, CONNECTICUT, A CORPORATION OF CONNECTICUT.

WOODWORKING-VISE.

1,229,659.

Specification of Letters Patent. Patented June 12, 1917.

Application filed January 11, 1917. Serial No. 141,798.

To all whom it may concern:

Be it known that we, EDMUND A. SCHADE and JOSEPH M. HANCE, citizens of the United States of America, residing at New Britain, Connecticut, have invented a new and useful Woodworking-Vise, of which the following is a specification.

This invention relates particularly to wood working vises, special objects of the invention being to provide such a vise which can be used with the vise jaws standing in the upright position as in the ordinary vise or can be turned on its side, with the vise jaws extending to the side, such construction being particularly useful for holding long pieces of timber on top of a work bench, the sidewise deposition of the vise jaws enabling the gripping of the end of a piece of lumber resting on the bench and the jaws, in their upright position, serving to hold the stock in the usual way.

Further objects are to provide a construction of this character which can be readily shifted from one position into another position and which will be strong and simple in construction.

Briefly the invention resides in the combination with a suitable supporting base provided with a headed holding bolt, of a detachable vise head having base portions at different sides thereof for engagement with the supporting base and provided with undercut open ended grooves for the reception of the headed portion of the holding bolt.

Other features of the invention will appear as the specification proceeds, attention being now directed to the accompanying drawings wherein we have illustrated the invention embodied in a practical and preferred form.

In said drawings:

Figure 1 is a perspective view of our vise with the jaws in the upright position, indicating a bench top to which the same is applied.

Fig. 2 is a perspective view of the base.

Fig. 3 is a rear view of the vise showing the same turned on its side.

Fig. 4 is a sectional view taken substantially on the plane of the line 4—4 of Fig. 1.

Fig. 5 is a fragmentary sectional view

taken substantially on the plane of the line 5—5 of Fig. 4.

Considering now the drawings in detail:

5 designates the base of the device, here shown as a substantially circular plate or disk adapted to be mounted on a bench or other support and provided with a circular upstanding rim or flange 6.

7 designates the detachable head portion 60 of the device carrying the vise jaws 8 and 9, one of said jaws 8 being shown as a fixed jaw and the other relatively movable in respect to the fixed jaw by means of an adjusting screw 10. When used for handling 65 timber the jaws are usually made extra wide and long substantially as indicated.

The vise head is constructed with base portions at different sides thereof for engagement with the supporting base. In the 70 present instance, three such base portions are shown, 11, 12 and 13, one on the bottom and two on opposite sides of the vise head, said base portions being substantially circular and of a size to fit within the annular flange 75 on the supporting base.

The vise head is detachably held to the base in the embodiment illustrated by a holding bolt 14 extending up through the supporting base and having an enlargement 80 or head 15 on the end thereof to fit within the undercut grooves 16 cut into the base portions on the head, said grooves being open at their outer ends as indicated at 17 and extending radially inward to substantially the centers of the base portions so as to permit of the ready engagement and disengagement of the vise head on the holding bolt and the swiveling of the vise head on said bolt and supporting base. Furthermore these undercut grooves for the holding bolt preferably open through the rear of the head so as not to mar the appearance or weaken the front or jaw portion of the head.

95 The holding bolt may be secured in holding position by suitable means such as a winged clamping nut 18 engaged on the lower threaded end of the bolt and having a bearing against a washer 19 resting against 100 the underside of the bench. As this securing nut and bolt serve to clamp all the parts

firmly together on the bench or other support it is only necessary, to install the device, to simply bore a hole of the proper size to receive the bolt in the bench and then assemble the parts in the relation illustrated.

- 5 It will be apparent from the illustration and from what has been said that the vise head will freely swivel on the supporting base and can be clamped in any desired angular relation by simply setting up the clamping nut. When it is desired to work with the vise jaws extending to the side instead of upright as in the first view, it is merely necessary to loosen the clamping 10 screw far enough to enable the vise head being lifted or tilted to disengage the base portion thereon from engagement in the confining flange on the supporting base, whereupon, the vise head can be withdrawn laterally from engagement with the holding bolt and then be turned on one side or the other to engage the base portion thereof with the supporting base and holding bolt.

In order to prevent the holding bolt from 25 dropping down when the vise head is withdrawn and to support it in proper position for reengagement with the vise head when the same is applied thereto we have provided a relatively light helical spring 20 surrounding the bolt and designed to support the bolt with the head thereof above the plane of the confining flange on the base and in position to readily engage in the undercut grooves in the sides of the vise head. This spring is 30 shown as having a bearing at its lower end on a washer 21 resting on the recessed central portion of the base and as bearing at its upper end against the under side of the head of the bolt.

- 35 40 Another advantageous feature of our invention is the provision of a separately formed nut 22 for the operating screw, said nut being shown as formed with a laterally enlarged base 23 fitting into an undercut 45 channel 24 extending inward from the rear of the head of the base. The forward end of the base portion of this nut has a bearing against the solid metal at the forward end of the channel at 25 and disengagement of 50 the nut from such position is prevented in the illustration by a pin 26 driven up through a passage in the bottom of the head into position in rear of the rearward portion of the base of the nut. With this construction it is possible upon removal of this pin to withdraw the nut rearwardly and thus the nut is made readily renewable in case of breakage or injury. The base of the 55 nut is shown connected with the nut portion 60 proper by means of a relatively narrow neck or shank portion 27 so that said nut is substantially centrally located within the passage 28 through which the shank 29 of the movable jaw passes and the undercut channel for the nut base is shown located in a

plane below the bottom of the passage 28 so as not to interfere with the sliding action of the shank jaw on the bottom of said passage.

From the foregoing it will be apparent 70 that the vise of our invention is very simple and practical.

What we claim is:

1. In a vise, a substantially circular supporting base, a vise head having a substantially circular base portion for engagement with the circular supporting base, said supporting base and the base portion on the head having substantially circular engaging portions rotatably confining the vise head on the supporting base, said circular base portion on the head having an open ended undercut slot extending centrally thereinto, a holding bolt centrally located on the supporting base and having a head 80 engageable in said undercut slot, securing means engaging said bolt to cause said bolt to seat the base portion of the vise head firmly on the supporting base and spring means for yieldingly supporting the bolt 85 with the head thereof in an upright position when the vise head is detached therefrom, to thereby enable the ready engagement of the vise head with the head of the supporting bolt and with the supporting 90 base aforesaid.

2. In a vise, a supporting base having an upstanding flange, a vise head having a base portion engageable with the upstanding flange on the supporting base and provided with an undercut open ended slot, a holding bolt having a head engaged in the undercut slot, means for securing said bolt in holding engagement in the undercut slot and a spring supporting the bolt with the head 105 thereof standing above the flange of the supporting base.

3. In a vise, a substantially circular supporting base, a vise head having a substantially circular base portion for engagement 110 with the circular supporting base, said supporting base and the base portion on the head having substantially circular engaging portions rotatably confining the vise head on the supporting base, said circular base 115 portion on the head having an open ended undercut slot extending centrally thereinto, a holding bolt centrally located on the supporting base and having a head engageable in said undercut slot, securing means engaging said bolt to cause said bolt to seat the base portion of the vise head firmly on the supporting base, and a spring engaged beneath the head of the holding bolt adapted to yieldingly support said bolt with the head 120 thereof in an elevated position when the vise head is removed from the supporting base.

4. A vise, comprising a supporting base, having an upstanding annular flange, a vise 130

head having substantially circular base portions on different sides thereof rotatably fitting within the upstanding annular flange on the supporting base, said vise head further having undercut grooves extending radially inward through the circular base portions aforesaid, substantially to the centers thereof and said undercut grooves being open at the outer ends thereof, a pivot bolt located centrally of the supporting base and

having an enlarged head engageable in the undercut grooves, securing means engaging the pivot bolt to cause the head of said bolt to draw the circular base portion of the vise head down to a firm seat within the upstanding flange of the supporting base and coöperating relatively movable clamping jaws on the vise head.

EDMUND A. SCHADE.
JOSEPH M. HANCE.
